(57) **CLAIM**

The ornamental design for a brick tile, as shown and described.

DESCRIPTION

FIG. 1 is a first perspective view of a brick tile of the present invention taken generally from the top and left;

FIG. 2 is a second perspective view thereof taken generally from the bottom and left;

FIG. 3 is a front view thereof;

FIG. 4 is an elevational view of the left side thereof;

FIG. 5 is an elevational view of the right side thereof;

FIG. 6 is a rear view thereof;

FIG. 7 is a top view thereof; and,

FIG. 8 is a bottom view thereof.
